US00D815410S

(12) **United States Design Patent** (10) **Patent No.:** **US D815,410 S**
(45) **Date of Patent:** ** *Apr. 17, 2018

(54) **INSOLE FOR A SHOE**

(71) Applicant: **S.C. JOHNSON & SON, INC.**,
Racine, WI (US)

(72) Inventors: **Caroline M. J. Fischer**, Mosbach (DE);
Ryan P. Kane, Shenzhen (CN); **Noud
Claassen**, Eindhoven (NL)

(73) Assignee: **S. C. Johnson & Son, Inc.**, Racine, WI
(US)

(*) Notice: This patent is subject to a terminal disclaimer.

(**) Term: **15 Years**

(21) Appl. No.: **29/591,514**

(22) Filed: **Jan. 20, 2017**

Related U.S. Application Data

(60) Continuation of application No. 29/529,865, filed on Jun. 11, 2015, now Pat. No. Des. 781,041, which is a division of application No. 29/478,887, filed on Jan. 9, 2014, now Pat. No. Des. 734,010.

(57) **CLAIM**

The ornamental design for an insole for a shoe, as shown and described.

DESCRIPTION

FIG. 1 is a top isometric view of an insole for a shoe showing our new design;

FIG. 2 is a side elevational view of the insole of FIG. 1;
FIG. 3 is an opposite side elevation view of the insole of FIG. 2;

FIG. 4 is a rear elevational view of the insole of FIG. 1;

FIG. 5 is a front elevational view of the insole of FIG. 1;
FIG. 6 is a top plan view of the insole of FIG. 1; and,

FIG. 7 is a bottom plan view of the insole of FIG. 1.

The broken lines in the drawings depict environmental subject matter only and form no part of the claimed design.

1 Claim, 4 Drawing Sheets
